Application June 19, 1941, Serial No. 101,560

Term of patent 14 years

To all whom it may concern:

Be it known that I, Carl J. Uhrmann, a citizen of the United States of America and resident of Bellaire, county of Belmont and State of Ohio, have invented a new, original, and ornamental Design for a Bowl Candle Holder or Similar Article, of which the following is a specification, reference being had to the accompanying drawing forming part thereof, in which—

Figure 1 is a side elevational view, with parts broken away and shown in section, of a bowl candle holder or similar article, showing my new design, suspended prism pendants being shown in dotted lines at opposite sides of the article to

illustrate the suspension of said prisms about the periphery of said article, the remaining prism pendants having been omitted for convenience of illustration.

Figure 2 is a top plan view of the same; and
Figure 3 is a cross-sectional view taken on line
3—3 of Figure 1.

The characteristic features of the design are shown in full lines.

I claim:

The ornamental design for a bowl candle holder or similar article, substantially as shown and described.
